UNITED STATES PATENT OFFICE.

WINTHROP M. CHAPMAN, OF NEEDHAM, MASSACHUSETTS.

REPEATER.

SPECIFICATION forming part of Letters Patent No. 615,014, dated November 29, 1898.

Application filed March 17, 1898. Serial No. 674,176. (No model.)

To all whom it may concern:

Be it known that I, WINTHROP M. CHAPMAN, of Needham, county of Norfolk, and State of Massachusetts, have invented an Improvement in Repeaters, of which the following description, in connection with the accompanying drawings, is a specification, like letters and figures on the drawings representing like parts.

10 The present invention relates to electric signaling apparatus and is embodied in a repeater especially adapted for use in fire-alarm systems.

15 The object of the invention is to automatically receive and transmit signals where the signaling instruments are adapted to operate at one rate of speed and it is desired to transmit the signals at a different rate of speed.

20 In fire-alarm systems it is desirable to have the signals given as rapidly as possible; but in a great many systems steam-whistles and heavy mechanism for striking large bells are used in connection with other smaller apparatus for giving alarms. The steam-whistles 25 and bell-strikers cannot be made to work very rapidly, and as a consequence the rest of the apparatus in the system which is capable of acting much more rapidly has of necessity been timed to correspond to the requirements

30 of the slower-acting machines. In accordance with the present invention, however, all the apparatus that is capable of operating quickly may be so operated and the slower-operating machines need not be dispensed

35 with, but may be operated by the slower-transmitting mechanism which operates in response to the quick-operating devices. It can be so arranged that both the whistles, &c., and the smaller gongs, &c., may be located in the same circuit or in separate circuits, as desired, and it may be connected with one or several circuits.

40 The instrument embodying the invention consists of a main controlling device adapted 45 to operate in response to the impulses of signals received at the instrument, the said controlling device being adapted to act at each impulse so as to cause the operation of a device for setting a number of movable parts 50 in position to coöperate with a signal-repeating train capable of operating at any desired speed and to produce changes in a signaling

circuit or circuits by such coöperation, thereby transmitting the signal at any desired speed. The signaling-train is arranged to be 55 released by the said controlling device at the first impulse of the signal and to continue operating until the entire signal has been repeated.

For convenience I will term the movable 60 parts which coöperate with the signal-repeating train "recording-arms," since they practically record the signal which comes in front of the boxes in order that it may be transmitted by the signal devices as recorded. These recording-arms are arranged consecutively and are adjusted to the path of a traveling actuator, which is adapted at each impulse of a signal to engage one of said recording-arms and move the same to its operative position. 65 The said traveling actuator is provided with an escapement device, whereby it is caused to move only a certain predetermined distance at each signal impulse, and thus consecutively act upon certain recording-arms to set or move 70 the same. In order to provide for the longer intervals between the groups and rounds of a signal, the said escapement device which controls the actuator is also movable and is itself controlled in its movement by a timing 75 device, which permits the said escapement, bearing with it the traveling actuator, to move a certain predetermined distance at each interval longer than the interval between successive impulses of a single group. 80 The said controlling device is of novel construction and forms a feature of the present invention. The signal-repeating mechanism comprises a movable member carrying a circuit-controlling device and adapted to move 85 said circuit-controlling device in a path adjacent to the path of the recording-arms, so that said circuit-controlling device may engage with such of the recording-arms as have been moved by the actuator into their operative 90 position. Thus as a signal is received the actuator will cause recording-arms corresponding in number and spacing to the impulses of the signal received to be moved into their abnormal or operative position, and the signal-repeating mechanism, which is started at the first impulse of the signal, follows at 95 any desired speed and repeats the signal which has been thus recorded.

The invention further relates to a timing device of novel construction and arrangement, which will be hereinafter more fully described.

Figure 1 shows a front elevation of an apparatus embodying the present invention used in conjunction with an ordinary fire-alarm repeater, the slow-moving repeating mechanism being for the most part indicated in dotted lines. Fig. 2 is a plan view of that part of the mechanism embodying the present invention, which is shown in Fig. 1 above the dotted line A B, some of the parts being shown in section and only two recording-arms being shown. Fig. 3 is a sectional front elevation of the mechanism shown in Fig. 2, the section being mainly taken on the dotted line C D, the slow-moving arm and attached parts, however, being shown in elevation. Fig. 4 shows a front elevation of the apparatus similar to Fig. 1, (it being shown in this instance as an independent machine and not in combination with an ordinary repeater,) but with the parts in the relative positions they will occupy after the first impulse of a signal has been received. Figs. 5, 6, and 7 are details to be referred to. Figs. 8, 9, 10, 11, 12, and 14 are modifications to be referred to; and Fig. 13 is a detail in elevation, showing a timing device of novel construction, which forms part of the present invention.

When the machine is used in connection with and as a part of a regular repeater, as shown in Fig. 1, the regular repeater motor or train (indicated by dotted pitch-circles in the lower left-hand part of Fig. 1) serves to actuate the recording mechanism of the present invention and to control the signaling mechanism. The repeater shown will not be herein described in detail, since it forms no part of the present invention. For convenience I have shown a repeater like that described in a prior patent granted to me January 12, 1897, No. 575,025. It is obvious, however, that the mechanism embodying the present invention may be used with any repeater or independently, as indicated in Fig. 4.

As shown in Fig. 1, the repeater-train, which, as stated, serves to actuate the recording mechanism, is controlled by a movable arm 8, co-operating with a stop-arm b' in the usual way. Where a rigid stop-arm of this kind is used, however, the impact of the moving member controlled thereby at the end of a revolution is sufficient to cause a detrimental shock, so that the parts are quickly worn out or gotten out of adjustment, and this defect may be obviated by providing the stop-arm 8 with a cushioned engaging member z, as shown in Fig. 14, the said member being cushioned in any suitable way, as by the spring z'.

When the machine is used as a separate mechanism independent of a regular repeater, as shown in Fig. 4, an electromagnet a, connected into a signaling-circuit (not shown)

and responsive to the impulses of signals, serves to control a motor or train for the same purpose as the repeater-train in Fig. 1. The said electromagnet a is provided with an armature a', secured to a holding-arm a², pivoted to one side of the frame E of the machine at a³. The locking projections a⁴ and a⁵ are secured to and movable with the armature-holding arm a² and constitute a double detent of the usual type for the signaling-mechanism controller.

A retractile spring a⁶ serves to move the armature a' into its retracted position, when the magnet a becomes demagnetized. A suitable motor, such as the train of wheels indicated by dotted circles on the left lower part of Fig. 4, is adapted to rotate the shaft b of the controlling mechanism above described in the direction of the arrow. An arm b' is secured to this shaft b, and a projection b² is formed on the end of said arm b' and, together with the projections a⁴ and a⁵, forms the releasing device controlled by the electromagnet a of the mechanism shown in Fig. 4. A cam c (shown by dotted lines) is secured to the shaft b and is adapted to engage a roll on the end of an arm c' and so wind up a time-train or timing device (indicated by dotted lines) on the right-hand side of the electromagnet a. An eccentric-pin d is formed on the front end of the shaft b, and as said shaft b revolves at each impulse of a signal this eccentric-pin d, by means of suitable connecting parts, controls the mechanism shown in the upper parts of Figs. 1 and 4.

The lower end of a connecting-rod d' is connected to the eccentric-pin d, and its upper end is connected to the end of one member e (see Fig. 7) of a bell-crank lever e e', pivoted at e² in a holding-piece e³, secured to the main frame E of the machine. One end of another connecting-rod e⁴ is connected loosely with and free to turn in the end of the member e' of the bell-crank lever pivoted at e². The other end of said rod e⁴ is loosely connected at e⁵ (see Figs. 2 and 7) with the rocking actuating-arm and is adapted to actuate the same, as will be described.

A hollow stud f is fastened securely into the back side of the frame E, and the connecting-rod e⁴ passes freely through the hole in the center of said stud f. A crown ratchet-wheel f' is loosely pivoted and free to turn on the stud f. Said ratchet-wheel f' is provided with any suitable number of teeth f² on one of its faces and with pins on the other, there being shown herein sixty teeth and twenty pins f³, arranged at equal distances from each other on its other face. A carrying-piece g is also loosely pivoted to and free to turn on the stud f, and said carrier g has a rocking arm g', pivoted on it at g², the said rocking arm constituting the actuating-arm, as stated. The said arm g' is provided at or near its extremities with two projections g³ and g⁴, said projections being adapted to alternately engage with the teeth f² of the

crown ratchet-wheel f' as the said arm g' is rocked on its pivot g^2 . An actuating projection g^5 , adapted to coöperate with the recording-arms h^2 , is also formed on one end of the 5 rocking arm g' and extends a little distance beyond the projection g^4 . The carrying-piece g has an arm g^6 , Fig. 7, extending some distance beyond the pivot g^2 , and said arm g^6 carries a roll g^7 at its extremity. At the opposite extremity from the roll g^7 the carrying-piece g is turned at right angles, as at g^8 , and said part g^8 is slotted and acts merely as an extra guide for the rocking arm g' . A bridging-piece g^9 , formed integral with the rest of the carrying-piece g , extends from the turned portion g^8 to a corresponding portion near the pivot g^2 , and said bridging-piece g^9 serves merely to carry a stud g^{10} and a pin g^{11} . (See 15 Figs. 2 and 11.)

20 A support for the movable recording-arms, herein shown as a ring h , is secured rigidly to the back side of the frame E by means of the three supporting-studs 3 , Figs. 1 and 4, said support being concentric with the crown ratchet-wheel f' . Secured to the back side 25 of the ring h are a number of holding-blocks h' , arranged at equal distances from each other around said ring h , and each one of these holding-blocks h' carries a movable recording-arm h^2 , loosely pivoted to it at h^3 , Figs. 2 and 5. For clearness only a few of these recording-arms h^2 are shown in most of the views. The said recording-arms h^2 are provided at 30 one end with engaging portions h^4 to coöperate with the rocking recording-arm g' and at the other end with engaging portions h^5 to coöperate with the signaling mechanism, as will be hereinafter shown. The said portions h^4 of the recording-arms are arranged in position to be successively acted on and moved 35 from their normal to their abnormal position by the extension-piece g^5 on the rocking arm g' as said rocking arm g' is rocked in one direction. In order that said recording-arms 40 may be held in either their normal or abnormal positions when moved into either, they are shown in Fig. 5 as provided with V-shaped projections h^6 , coöperating with plugs h^7 , provided with springs h^8 , thus constituting practically a snap locking device, which will not 45 only hold the arms in either position, but will tend to carry them from a central position to either extreme position if sufficient impulse is given to move them across the center. It 50 is practicable, however, to accomplish substantially the same purpose by frictionally supporting the said arms on their pivots, such a construction being shown in Fig. 8, wherein the arms h^2 are pivoted between a pair of ears 55 or lugs which are near enough together to frictionally engage the opposite sides of the said arm and prevent the same from being accidentally moved in either direction.

55 A segment i is pivoted to the frame E , and said segment i is connected by means of a connecting-rod i' to the arm c' of the time-train. (Shown in the lower left hand of Figs. 1 and

4.) The flange i^2 of said segment i is so disposed as to be in the path of and adapted to engage the pins f^3 on the front side of the 70 crown ratchet-wheel f' . Two gaps i^3 and i^4 are cut through this flange i^2 , and two light flat springs i^5 and i^6 are secured to the inner side of the said flange i^2 (see Fig. 6) and are arranged, respectively, to bridge the gaps i^3 and 75 i^4 , the free ends standing normally far enough away from the flange to permit the pins f^3 to pass between them and the flange. When the time-train after being wound up has run down a sufficient distance, the segment i has 80 reached such a position as to allow one of the pins f^3 , which is in engagement with the flange i^2 , to pass under the loose end of one of the springs i^5 i^6 , and so pass through one of the gaps i^3 i^4 . This allows the crown ratchet- 85 wheel to be rotated the distance between two of the pins f^3 , as the succeeding pin will engage one of the springs i^5 i^6 , and so be prevented from passing through the corresponding gap in the flange i^2 .

90 The time-train shown in Fig. 4 is of the usual type, an electromagnet a being adapted to control the action of a train of wheels adapted to rotate a shaft b , and thereby, by means of an eccentric-pin d , to give motion to the 95 connecting-rod d' . This main train of wheels is also adapted to wind up a time-train. A timing device of novel construction and arrangement, however, is herein shown and forms a feature of the present invention. In 100 this construction, which is shown in Fig. 13, the main train of wheels is entirely dispensed with, motion being given to the connecting-rod d' directly from the action of the electromagnet a and the winding of the time-train 105 being accomplished in another way. As shown in Fig. 13, the electromagnet is provided with an armature a' , fast to a holding-piece a^2 , pivoted at a^3 and provided with a retractile spring a^6 . Two arms w w' are 110 formed integral with the armature-holding piece a^2 . As the armature a' is retracted by the spring a^6 the end of the arm w engages with a spring-pressed pawl w^2 , secured to an arm w^3 , pivoted at w^4 . The lower end of the 115 connecting-rod d' is also loosely secured to the arm w^3 , and as the arm w , engaging the pawl w^2 , swings the arm w^3 downward a downward motion is also imparted to the connecting-rod d' . After the arm w^3 has been swung 120 downward a sufficient distance the end of the arm w disengages from the pawl w^2 and a spring w^6 swings the arm w^3 , and consequently the connecting-rod d' , upward to its original position, thus completing the motion of the rod 125 d' . The winding of the time-train may be accomplished in several different ways, and in Fig. 13 this is shown as being done by the action of the shaft b^3 in rotating. An arm x is made fast to the wheel b^4 and is adapted at each 130 revolution of the shaft b^3 to engage with one of a number of pins x' . These pins x' are secured at equal distances from each other in a wheel x^3 and project laterally therefrom. This

- pin-bearing wheel x^2 is pivoted loosely on a shaft x^3 , and one end of a spring x^4 is secured to said wheel x^2 at x^5 , the other end of said spring x^4 being fast to the shaft x^3 . A ratchet-wheel x^6 (shown in dotted lines) is secured rigidly to the frame of the machine, and a pawl x^7 , pivoted to the wheel x^2 , is adapted to engage the teeth of said ratchet-wheel x^6 . As the spring x^4 is liable at times to be wound up faster than it runs down, suitable means are provided to prevent it being overwound. These consist of a segment of a wheel x^8 , secured on the shaft x^3 , and a pin x^9 in the end of the pawl x^7 . When the spring x^4 is wound up a certain distance by the action of the projection x on the pins x^9 , the pin x^9 will become engaged with the segment x^8 and so raise the pawl out of engagement with the ratchet-wheel x^6 and so prevent further winding.
- 20 The action of the spring x^4 in unwinding tends to rotate a ratchet-wheel y in the direction of the arrow. An arm y' is loosely pivoted concentric with the ratchet-wheel y , and a pawl y^2 is pivoted on said arm y' at y^3 . In its normal condition the pawl y^2 engages the teeth of the ratchet-wheel y , and the time-train is brought to rest and held in its normal position by the arm y' engaging a pin y^4 on the frame of the machine. A pawl y^5 is loosely pivoted at y^7 to a suitably-flattened portion of a sliding rod y^8 , arranged to slide freely in two guiding-pieces y^9 and y^{10} , secured to a suitable part of the frame of the machine. (Not herein shown.) The connecting-rod y^{12} is loosely pivoted at one end to the pawl y^2 and at the other end to the flattened portion of the sliding rod y^8 . When the armature a' is retracted by the spring a^6 , the arm w' engages the pawl y^5 and causes a sliding movement of the rod y^8 , which is transmitted through the rod y^{12} to the pawl y^2 , forcing the said pawl y^2 out of engagement with the teeth of the ratchet-wheel y . As the pawl y^2 is thus disengaged a spring y^6 , acting on the arm i , 45 swings said arm i and also the arm y' and attached parts upward, and the spring x^4 is free to rotate the ratchet-wheel y and the rest of the time-train. After being disengaged from the ratchet-teeth the pawl y^2 is held out of 50 engagement until as the arm y' is moved upward the end of the pawl y^2 engages with a beveled block y^{10} on the frame and is swung back, so that it can engage the teeth of the ratchet-wheel y . The arm y' will now be 55 moved downward with the ratchet-wheel y , and as the rod i connects the arm y' with the arm i the said arm i will be moved also. This arm i corresponds to the segment i in the main drawings and its motion serves to release the 60 pins f^3 , as in the main drawings. At each impulse of a signal the pawl y^2 will be disengaged and swung upward, as above described, but will finally come to rest after the completion of a signal as the arm y' engages the pin y^4 in the frame.
- 65 The operation of the device as thus far described is substantially as follows: Upon an

impulse of a signal the motor-shaft b makes one revolution, rocking the recording-arm actuator g' forward and back. Such rocking movement, as described, causes the said arm to move one of the recording-arms h^2 from its normal to its abnormal position and permits the arm g' to rotate a predetermined distance. This operation is repeated at each impulse of the first group of a signal, thus moving a number of said recording-arms equal to the number of impulses in the group, the recording-arms moved being equidistant from each other. The timing-train is so arranged that the segment i is restored to its normal position at each impulse before it has moved sufficiently far to permit one of the pins f^3 to reach the opening i^3 in the said segment, so that during the first group the crown-toothed wheel f' is retained stationary. At the end of the group, however, the interval between impulses is sufficiently long to permit the time-train to run down sufficiently far to allow the segment to travel upward, Fig. 4, and move to such a position that the opening i^3 comes in line with one of the pins f^3 , thus permitting the crown-toothed wheel f' to rotate until the succeeding pin f^3 is caught by the flange i^2 on the segment i or the bridging-spring i^5 . This rotation of the crown-tooth wheel carries with it the arm g' , so that at the next impulse the said arm will actuate a recording-arm at a distance from the last recording-arm moved which corresponds to the interval between the groups of the original signal. During the longer interval between complete rounds of a signal the segment i will be moved sufficiently far to permit the pin f^3 , which is engaged beyond the opening i^3 , to pass through the opening i^4 , thus producing a still greater interval between the recording-arms which have been moved. The same operation continues throughout the complete signal, so that the recording-arms are set ready to coöperate with the signaling mechanism, which will be hereinafter described, in such a manner that the signal is repeated by the said signaling mechanism at any predetermined speed.

The signaling mechanism consists, essentially, of a movable member actuated by a motor or train, which is normally held stationary, but released in response to the first impulse of a signal. The said movable member is provided with a device to coöperate with the recording-arms which have been moved, as above described, from their normal to their abnormal position, said device controlling the circuits over which the signal is to be repeated, so that each time said movable member is actuated by coming in contact with one of said arms it causes a change in the said circuit or circuits. This may be accomplished in any suitable or usual way, the circuit changes being either caused directly by the action of the said movable member or by a secondary motor controlled thereby.

The construction and arrangement herein shown to illustrate the invention are substantially as follows:

Referring to Fig. 2, it will be seen that the main frame of the machine is provided (in addition to the front plate E) with corresponding plates F and G, all three of said plates being secured together by suitable studs.

- 10 In Figs. 1 and 4 that part of the mechanism shown back of the dotted line C D in Fig. 2 is for the most part shown merely by dotted pitch lines to indicate the train of wheels, so as to avoid a multiplicity of lines. These parts are, however, clearly shown in Fig. 3, which is a sectional elevation taken on the line C D, Fig. 2. A winding-shaft k has its bearings in the main frame-plates E and F, and a winding-pinion k' is secured thereto and meshes with a corresponding winding-pinion k², secured to a shaft k³. The said shaft k³ has its bearings in the main frame-plates F and G, and two driving-wheels k⁴ and k⁵ are loosely mounted thereon. The 25 driving-wheel k⁴ is provided with a suitable pawl arranged to engage the teeth of a winding-ratchet-wheel k⁶, secured to the shaft k³. The driving-wheel k⁵ is secured to a spring-box k⁷, which incloses a suitable driving-spring. One end of the said driving-spring is secured to the spring-box k⁷ and the other end is made fast to the shaft k³. This arrangement allows the driving-spring to rotate the wheel k⁴ in one direction and the wheel k⁵ 30 in the opposite direction, and also allows either of the wheels k⁴ or k⁵ to revolve while the other is stationary. The wheel k⁴ meshes with a pinion k⁸, secured to a shaft k⁹, to which a wheel k¹⁰ is also secured. This wheel k¹⁰ 35 meshes with a pinion k¹¹, secured to a shaft k¹², to which a wheel k¹³ is also secured. This wheel k¹³ meshes with a pinion k¹⁴ on a shaft k¹⁵, to which an escape-wheel k¹⁶ is also secured, said escape-wheel k¹⁶ engaging with a 40 suitable pallet or escapement k¹⁷, adapted to regulate the motion of the train of wheels. The driving-wheel k⁵ meshes with a suitable pinion l, secured to a shaft l', having a wheel l² also secured to it. Said wheel l² meshes 45 with a suitable pinion secured to a shaft l³, having also a wheel l⁴ secured to it. The wheel l⁴ meshes with a suitable pinion on a shaft l⁵, to which a fan l⁶, adapted to regulate the motion of the train of wheels, is secured. 50 An arm m is secured to the shaft k¹² on the front side of the main frame-plate F and has formed on it a locking projection m', said projection m' being adapted normally to engage with a suitable part of the carrying-piece g 55 near the pivot g², and so prevent the shaft k¹², bearing the arm m, from revolving. A roll m² is shown as secured to a suitable projection on the arm m, and a movable pawl m³ is also loosely pivoted to said arm m at m⁴. 60 The said pawl m³ has a beveled portion m⁵, Fig. 1, formed near its extremity, and said beveled portion m⁵ is adapted to engage with

the movable recording-arms h² when said arms h² are in their abnormal positions, and to thereby cause a movement of the pawl. 70 As said pawl m³ disengages one of the arms h² after being actuated thereby the roll m² engages with said arm h² and causes it to be moved back to its original or normal position. The roll g⁷ is so disposed on the extension-arm g⁶ of the carrying-piece g as to move adjacent to the arms h² and just ahead of the actuating-arm g', and if through any cause any of the arms h² should be left in their abnormal position the said roll g⁷ will act 80 similarly to the roll m² and restore them to their normal positions. It may be desirable in some cases to have the arms remain in their abnormal positions between signals, and in this instance the rolls m² may be omitted. 85 The pawl m³ is also loosely connected at m⁶ with one end of a connecting-rod m⁷, Fig. 3, the other end of said rod m⁷ being connected loosely at n to one member n' of a bell-crank lever n' n². A slot n³ is formed in the arm 90 m, and in this slot n³ the bell-crank lever n' is pivoted at n⁴. The shaft k¹² has a central longitudinal opening from end to end, and a connecting-rod n⁵ passes freely through said opening. One end of the said connecting-rod n⁵ is loosely connected with and free to turn in the end of the member n² of the bell-crank lever n' n². The other end of the rod n⁵ is also loosely connected at o to one end of a releasing-lever o', pivoted at o² to a suitable 100 holding-piece secured to the back of the main frame-plate G. Two projections o³ and o⁴ are formed on the opposite end of the releasing-lever o'. An arm o⁵ is made fast to the back end of the shaft l³, and the end of this said arm o⁵ co-operates with the two projections o³ and o⁴ on the releasing-lever o', and this forms a releasing device that allows the shaft l³ to 105 make one revolution each time the pawl m³ on the arm m engages with one of the recording-arms h².

If desired, the circuit-changing devices may be operated directly by the movement of the pawl m³ instead of by a motor controlled by the movement of said pawl. As shown in 115 Fig. 12, the said pawl co-operates directly, as by a rod n⁵, with the circuit-changer, connection being shown as made by means of a lever t, pivoted at t', the members t³ and t⁴ of the circuit-changer being normally held together 120 by means of a spring t⁶. The said lever t is provided with a finger-piece or projection t⁵ coacting directly with the spring contact-piece t⁴, and the rod n⁵ in moving overcomes the stress of said spring and permits the contact 125 t⁴ to be separated from the contact t³, and thus open the circuit, and thereby repeat the signal which has been originally received and recorded.

The circuit-changer is shown as mounted 130 on an arm or standard t².

To change the circuit in response to the action of the train of wheels above described, a roll p of insulating material is shown in

Figs. 2 and 3 as firmly secured to the shaft b^3 , and this roll p has a gap p' formed in it lengthwise. A block p^2 of insulating material is secured rigidly to a suitable post fast to the frame-plates F and G, and on this said block p^2 a number of circuit-changing springs p^3 and p^4 are secured. These springs p^3 and p^4 represent a common circuit-changing device and are so arranged that normally the ends of the springs p^3 which overlap the ends of the springs p^4 stand over the gap p' in the roll p , and so the springs p^3 and p^4 are allowed to stay in contact. As the shaft b^3 rotates, carrying the roll p , the higher part of said roll p raises the springs p^3 from engagement with the corresponding springs p^4 , and so causes an impulse to be sent out or transmitted. A pin 4 is secured in the hub of the arm m . A light spring 5 is coiled loosely on the stud g^{10} on the carrying-piece g , and one end of said spring 5 is secured to the pin g^{11} and the other end thereof is made fast to the pin 4 on the arm m . This spring 5 does not act as a connection between the slow-moving arm m and the quick-moving receiving parts, as no such connection is needed. It merely serves to actuate the carrying-piece g and is connected to the slow-moving arm m , so that the movement of said arm m may keep the said spring 5 continually under tension, and so do away with the necessity of winding it up by hand.

Fig. 9 shows in detail a modification of the apparatus shown in Fig. 1, the quick-acting receiving mechanism being actuated and governed by a mechanism similar to the regular repeater mechanism shown in Fig. 1, with the repeating circuit-changers and coöperating parts of the repeater omitted, so that the repeating action of the regular repeater is dispensed with.

As shown in Fig. 9, the rod d' is connected directly to a part 12 of the releasing device for the repeater, its motion being governed by any one of the repeater-magnets, (not shown,) said magnets being connected to the rods 10. In the construction shown in Fig. 9 only one-half as many pins f^3 are needed in the ratchet-wheel f' as are used in that shown in Fig. 1, and the segment i and its coöperating parts are dispensed with, and an arm r is pivoted at 2, and the upper end of the rod i' is loosely connected to said arm. The arm r terminates in two projections r' and r^2 . On the projection r' two flat springs r^3 and r^4 are secured, and on the projection r^2 two corresponding springs r^5 and r^6 are made fast. An arm s is rigidly attached to the inner side of the main frame-plate E, and a movable piece s' is pivoted to the front side of said arm s at s^2 . Two pins s^3 and s^4 are secured in the movable piece s' and extend laterally therefrom, so as to be alternately in the path of movement of the flat springs r^3 , r^4 , r^5 , and r^6 on the arm r . Two other pins s^5 and s^6 are also secured in the movable piece s' and extend laterally there-

from and are so disposed on said piece s as to be alternately in position to engage the pins f^3 on the crown ratchet-wheel f' . Two notches s^7 and s^8 are formed in the movable piece s' and are adapted to alternately engage with a suitable projection on the end of a spring s^9 , secured to the arm s . When the arm r has been moved downward sufficiently far by the action of the time-train, the end of the flat spring r^3 engages with the pin s^3 on the movable piece s' and swings said piece s' on its pivot s^2 until the pin s^3 has swung out of engagement with the end of the spring r^3 . This movement has served to swing the movable piece s' sufficiently far so that the pin s^5 is moved out of engagement with the pins f^3 on the ratchet-wheel f' , and the pin s^6 on said piece s' is moved into the path of engagement of the pins f^3 . This allows the ratchet-wheel f' to be rotated half the distance between said pins f^3 or until the next succeeding pin f^3 engages with the pin s^6 on the movable piece s' . The projection on the end of the spring s^9 , engaging with either of the notches s^7 and s^8 , serves merely to hold the piece s' in position. The next movement of the movable piece s' will be caused by the action of one of the springs r^4 or r^6 acting on the pin s^4 , secured in the movable piece s' . This will swing the said piece s' back to its original position and allow the ratchet-wheel f' to rotate again the distance of three teeth on said wheel f' .

If it is desired to have both the quick-acting signal-giving machines, such as small gongs, &c., and the slow-acting signal-giving machines, such as steam-whistles and large bell-strikers, located in the same circuit, the quick-acting machine may be arranged to respond to breaks and closures in the circuits, such as would be caused by the ordinary circuit-changing contact, as hereinbefore described. The slow-acting machines could then be arranged to respond only to a change in direction of the current in the circuit, or, as it is commonly called, a "reversal" of the circuit. This may be accomplished by providing the apparatus with any of the common forms of circuit-reversing devices, as indicated in Fig. 10.

In Fig. 11 the projection m' , which is engaged by the arm g' to hold the signaling-train normally stationary, is shown as engaging a beveled portion 12 on the said arm g' , the object of this being to make the releasing of the arm m easier. A beveled portion on the projection m' engages with the beveled part 12 on the rocking arm g' , and these beveled parts acting together tend to help move the arm g' at its first impulse when the arm m is released.

I claim—

1. In a signaling device the combination with a series of recording-arms, of an actuator therefor having a rocking and also a lateral movement, a controlling device for causing a rocking movement of said actuator in response to the impulses of signals, and an

escapement device operated by said rocking movement of the actuator to determine the extent of the lateral movement of said actuator at each impulse, substantially as described.

2. In a signaling device, the combination with a series of recording parts, of an actuator therefor having a rocking and also a lateral movement, a controlling device responsive to impulses of signals for causing a rocking movement of said actuator, an escapement device of which said actuator constitutes the movable member, said escapement device determining the extent of the lateral movement of said actuator at each impulse, and means for moving bodily both members of said escapement, they being stationary with relation to each other, at predetermined intervals, substantially as described.

3. In a signaling mechanism, the combination with a series of recording-arms adapted to be moved into position to coöperate with a signal-repeating device of a controller responsive to circuit changes, of an actuator adapted to be rocked in response to the action of the controller and thereby move one of said recording-arms, means for moving said actuator laterally in a path adjacent to said recording-arms, an escapement device for determining the extent of said lateral movement of the actuator at each impulse, said escapement being operated by the rocking movement of said actuator, and means for starting the signal-repeating device, substantially as described.

4. In a signaling mechanism, the combination with a series of recording-arms adapted to be moved into position to coöperate with a signal-repeating device, of a controller responsive to circuit changes, an actuator adapted to be rocked in response to the action of the controller and thereby move one of said recording-arms, means for moving said actuator laterally in a path adjacent to said recording-arms, an escapement device comprising two members one of which is adapted to coöperate with the actuator during its rocking movement and thereby determine the extent of the lateral movement of the actuator at each rocking movement thereof, a controlling device for said escapement, a timing device coöperating with said controlling device to permit said escapement and the actuator stationary with relation thereto to move bodily after a predetermined interval between impulses, and an actuating-spring for moving said escapement laterally when so released, substantially as described.

5. In a signaling mechanism, the combination with one or more controllers, of the wheel f' bearing the teeth f^2 and the pins f^3 , the carrying-piece g bearing the actuating-arm g' and attached parts, the spring 5 , a series of movable recording parts, a controlling device coöperating with the said pins f^3 , and a timing device for operating said controlling device

at predetermined intervals after an impulse of a signal.

6. In a signaling mechanism, the combination of a controller responsive to circuit changes, a series of teeth or notches, an actuator having a rocking and also a lateral movement; said actuator being adapted to be rocked in response to the action of the controller, and being provided with projections adapted to alternately engage with the teeth or notches, such engagement serving to determine the extent of the lateral movement of said actuator at each of its rocking movements, and a series of movable parts so disposed as to be successively acted on by the actuator, substantially as described.

7. In a signaling mechanism, the combination of a controller, responsive to impulses of signals, an actuator having a rocking and also a lateral movement, and adapted to receive its rocking movement in response to the action of the controller, and a series of teeth or notches adapted to engage with the said actuator, thereby determining the extent of the lateral movement thereof at each impulse, an actuating-spring adapted at all times to move the said rocking arm laterally, but only allowed to do so at each rocking movement of said actuator, and a series of movable parts so disposed as to be successively acted on by the actuator, substantially as described.

8. In a signaling mechanism, the combination of a controller, responsive to impulses of signals, an actuator having a rocking and also a lateral movement, and adapted to receive its rocking movement in response to the action of the controller, and a series of teeth or notches adapted to engage with the said actuator, thereby determining the extent of the lateral movement thereof at each impulse, an actuating-spring adapted at all times to move the said rocking arm laterally, but only allowed to do so at each rocking movement of said actuator, a series of movable parts so disposed as to be successively acted on by the actuator, and a series of pins or projections also secured to said teeth or notches, a controlling device for said teeth or notches, co-operating with said pins, a timing device for governing said controlling device to permit the said teeth or notches, and also the actuator, stationary with relation thereto, to move at predetermined intervals after an impulse, substantially as described.

9. In a signaling mechanism the combination with a series of recording-arms forming part of a signal-repeating device said arms being adapted to be moved into position to coöperate with said signal-repeating device, of a controller responsive to circuit changes, an actuator adapted to be rocked in response to the action of the controller, and thereby move one of said recording-arms, a spring for moving said actuator laterally in a path adjacent to said recording-arms, said spring being at all times kept in operative condition

by the action of the signal-repeating device, an escapement device for determining the extent of said lateral movement of the actuator at each impulse, and operated by the rocking movement of said actuator, and means for starting the signal-repeating device, substantially as described.

10. In a signaling mechanism, the combination with a series of recording parts adapted 10 to be moved into position to coöperate with a signal-repeating device, of an actuator for said recording parts, a controller for governing the movement of said actuator in response to impulses of signals, an escapement device 15 comprising an escape-wheel and a movable pallet therefor, said pallet comprising also the actuator for the recording parts, a controlling device for said escape-wheel, a timing device for operating said controlling device to permit 20 said escape-wheel and also its movable pallet to move at predetermined intervals after an impulse of a signal, substantially as described.

11. In a signaling mechanism, a controller, a timing device, and a governing part adapted 25 to govern said signaling mechanism, means for allowing said governing part to positively engage said timing device, means governed by the controller for positively disengaging said governing part from the timing device, 30 and means for moving the governing part when so disengaged in the opposite direction to that of the timing device, and means for positively reengaging said governing part with said timing device, so that the same 35 will be restored thereby, substantially as described.

12. In a signaling mechanism, a controller, a governing part adapted to govern said signaling mechanism, a timing-motor provided 40 with a ratchet-wheel adapted to be moved by said timing-motor, said governing part being provided with means adapted to positively engage it with said ratchet-wheel, and be moved therewith, means governed by the controller for positively disengaging said governing part from said ratchet-wheel and means for moving said governing part, when so disengaged, in the opposite direction to that of the ratchet-wheel to a predetermined point, 45 50 and means for positively reengaging said ratchet-wheel and said governing part, after said governing part has been moved back to the said predetermined point, substantially as described.

55. 13. The combination with a signaling mechanism and a controller therefor, of a governing part adapted to govern said signaling mechanism, and means for moving said governing part in one direction to a predetermined point, a timing-motor carrying the toothed wheel y and adapted to rotate said wheel in one direction, the arm y' , pawl y^2 and attached parts and spring therefor, the beveled block y^6 , and means governed directly 60 65 by the controller for positively disengaging said pawl y^3 from the ratchet-wheel y , substantially as described.

14. The combination with a repeater, of a series of movable signal-recording parts, the recording mechanism comprising an actuator 70 adapted to successively move said recording parts from a normal to an abnormal position at each movement of the repeater, a secondary repeating mechanism adapted to coöperate with said recording parts when in their abnormal positions, and means for connecting said recording mechanism with movable parts of the repeater, substantially as described. 75

15. In a signaling mechanism, the combination of a recording device and a movable circuit-controlling device with a series of movable recording parts, said recording device being adapted to successively move said recording parts into position to coöperate with and actuate said movable circuit-controlling 80 85 device, and means movable with said circuit-controlling device for restoring the recording parts to their original position, substantially as described.

16. In a signaling mechanism, the combination with a signal recording and transmitting device, of a series of movable recording parts for said recording device, and a movable part for said transmitting device having secured thereto the roll m^3 , the pawl m^3 , the bell-crank lever n' , n^2 , and the rod m^7 , the roll m^2 and the pawl m^3 being adapted to coöperate with the movable recording parts substantially as described. 90

17. In a signaling device, the combination 100 with a series of recording parts; of an actuator for said recording parts, said actuator being capable of two separate and distinct kinds of motion; a controlling device for imparting one kind of motion to said actuator in response to impulses of signals; and an escapement device operated by the movement first imparted to said actuator to determine the extent of the other kind of motion thereof, substantially as described. 105 110

18. In a signaling device, the combination 115 with a series of recording parts; of an actuator for said recording parts, said actuator being capable of two separate and distinct kinds of motion; a controlling device for imparting one kind of motion to said actuator in response to impulses of signals, and to thereby cause said actuator to move one of said recording parts from normal to abnormal position; an escapement device operated by the movement first imparted to said actuator to determine the extent of the other motion thereof; and means for restoring said recording parts to their normal positions, substantially as described. 120 125

In testimony whereof I have signed my name to this specification in the presence of two subscribing witnesses.
